UNITED STATES PATENT OFFICE.

EDWARD B. ROTH, OF ST. LOUIS, MISSOURI.

RETORT FOR TREATING OIL SHALE.

Application filed December 19, 1924. Serial No. 756,892.

This invention relates to retorts for treating oil shale.

In the treatment of oil shale in order to vaporize and remove the oil therefrom various problems and requirements are encountered and, in order to obtain the best results, it is essential or desirable that the feed of the shale to and through the retort should be continuous; that the oil vapors should be produced at the lowest possible temperature and removed at once; that the heat should be applied uniformly; that the shale should be prevented from becoming gummed or coagulated in cakes, and should be reduced to a proper degree of fineness preferably so that it will pass through a quarter inch mesh screen; that it should be dried and pre-heated to a degree of temperature approximating the degree of temperature at which the first oil vapors are about to separate from the shale and rise; that the shale should be continuously agitated and propelled through different zones of progressively increasing heat; that the vapors be withdrawn quickly from the retort and from the different zones thereof.

Experience has demonstrated that the longer the shale is exposed to heat and the slower the heat is applied in the respective zones proportionately better results are obtained, and that the vapors from some of the shale components separate and rise under the influence of lower heat than from others; and, further, that the apparatus should be equipped with means for varying the speed of movement of the shale therefrom.

An object of the present invention is to provide an improved apparatus embodying structure for the performance of all of the above-mentioned operations, in a highly efficient and satisfactory manner so that the apparatus can be used commercially and profitably.

Specifically, an object of the invention is to provide an improved retort for the treatment of oil shale divided into compartments subjected to a higher degree of heat progressively from the compartment which the shale first enters to the compartment from which the shale is discharged, and having shale propelling and actuating devices in the compartments respectively, by the operation of which the shale is moved through all of the zones of heat and discharged from one

compartment to another and finally from the retort, in combination with means for rapidly removing the oil vapors from the retort. The invention is equally useful in the treatment of lignite and other materials containing matter that will vaporize.

Other objects will appear from the following description, reference being made to the accompanying drawings, in which

Fig. 1 is a plan view of one embodiment of the invention.

Fig. 2 is a side elevation.

Fig. 3 is a vertical sectional view.

Figs. 4, 5 and 6 are horizontal sectional views on the lines 4-4, 5-5 and 6-6 respectively of Fig. 3.

The invention as shown comprises an outer cylindrical wall 1, an inner wall 2 concentric with the outer wall and spaced therefrom, an upper end wall or cover 3 for the inner cylinder 2 and an upper end wall or cover 4 for the outer cylinder 1. A lower end wall 5 closes the lower end of the inner cylinder 2 and with said cylinder 2 and a wall 6 forms a combustion chamber containing a burner 7 to which fuel is supplied through a pipe 8. The upper end walls of the covers 3 and 4 are removable.

A spacing ring 9 forms a partition closing communication between the space between the inner and outer walls below said ring and the space between said walls above said ring. The interior of the retort above the lower wall 6 is divided into a number of compartments by horizontal partitions 10, 11 and 12, which compartments are subjected to progressively decreasing heat from the top toward the combustion chamber. The temperature of the heated air and vapors gradually decrease as they rise to the top of the device; so that the compartments are subjected to progressively increasing heat from the top toward the bottom. A shaft 13 extends axially through the device having its lower end journaled in a bearing 14 and its upper end connected by a clutch 15 with a drive shaft 16. A number of openings 17 through the inner cylinder 2 permit the vapors to pass from the several compartments to the space between the inner cylinder 2 and the outer cylinder 1 above the partition ring 9 from which space the vapors pass through outlets 18 to a condenser. The openings 17 are near the upper ends of the

respective compartments so that while the rising vapors will pass through said openings the shale will not.

A number of arms 19 extend from the shaft 13 in each of the compartments and rotate with said shaft. The arms 19 in the upper compartment support flights 20 designed and arranged to propel the shale delivered into the upper compartment toward the center, where the shale drops through slots or openings 21 in the partition 10 to the next compartment. The arms 19 in the compartment receiving the shale from the slots or openings 21 has flights 22 which propel the shale outwardly upon the partition 11 to slots or openings 23 through which the shale drops to the next compartment. The arms 19 in the compartment receiving the shale from the slots or openings 23 have flights 24 which propel the shale inwardly upon the partition 12 to slots or openings 25 through which the shale drops into the next and final compartment. From the lower compartment the shale is propelled outwardly by flights 26 and is discharged through openings 27 in the inner cylinder wall 2, being received in a water-seal 28 which prevents the vapors from escaping and at the same time permits removal of the waste products of the shale.

The shale is delivered into the upper compartment by a spiral conveyor 29 operating within a tubular passage 30. As the shale completely fills the spiral space of the conveyor it forms a seal to prevent the vapors from escaping thereby.

The partitions 10, 11 and 12 are removably supported upon brackets 31 and have notches 32 formed in their edges to permit insertion and withdrawal of the partitions.

The shale is conveyed to this apparatus by the conveyor 30 in a dry, preheated state and, due to the formation of the various series of flights, is propelled at the proper rate of speed through the different heated zones or compartments, the heat of which progressively increases from the upper compartment to the lower one. In moving from its point of delivery into the device to the point of discharge therefrom the shale is propelled over a comparatively long distance and is subjected to heat so that the vapors which separate and rise at a comparatively low degree of heat are caused to do so and pass from the upper compartment through the openings 17. Each compartment is subjected to a higher degree of heat than the one from which it receives the shale, and the last compartment is subjected to such a degree of heat that practically all of the oil is vaporized and discharged through the openings 17. During the operation of the device the feed of the shale thereto is continuous. The shale is kept moving through the device continuously and is con-

tinuously agitated so that each particle of the shale is subjected to the same heat as every other particle and is given the required time of exposure to obtain best results.

The present invention, containing a plurality of compartments subjected respectively to progressively increasing heat through which the shale is passed, possesses many advantages over that type of retorts including a single compartment. In the single compartment type of retorts the vapors that arise at the lower heat are subjected to the maximum heat required to vaporize the ingredients requiring highest degree of heat, thereby destroying the vapors that arise at low heat.

The invention may be used for various purposes such, for instance, as a roaster, or for drying substances such as clay and other substances. I claim the invention irrespective of the uses to which it is applied.

The invention possesses numerous other advantages and obtains all of its intended objects and purposes in an efficient, economical and profitable manner. The device may be varied as to size and number of compartments, and in various other particulars without departure from the nature and principle of the invention. I do not restrict myself unessentially, in this or other respects, but what I claim and desire to secure by Letters Patent is:—

1. A device of the character described comprising an outer casing wall, an inner casing wall within and spaced from the outer wall and having openings to the space between said walls, a number of horizontal partitions within said inner wall provided with openings therethrough respectively and forming compartments each communicating through said first named openings with the space between said walls, a pair of spaced top walls connected with said outer and inner walls respectively, and having the space between them communicating with the space between said outer and inner walls, a rotary vertical shaft extending axially through said top walls and said partitions, an agitator device attached to said shaft above each of said partitions, a device for feeding material through said top walls above the upper partition into said inner casing wall, and heating means enclosed within said inner casing wall below the lowest compartment.

2. A device of the character described comprising an outer casing wall, an inner casing wall within and spaced from the outer wall and having openings to the space between said walls, a number of horizontal partitions within said inner wall provided with openings therethrough respectively and forming compartments each communicating through said first named openings

with the space between said walls, a pair of spaced top walls connected with said outer and inner walls respectively, and having the space between them communicating with the space between said outer and inner walls, a rotary vertical shaft extending axially through said top walls and said partitions, an agitator device attached to said shaft above each of said partitions, a device for feeding material through said top walls above the upper partition into said inner casing wall, a water sealing device at the lower ends of said inner and outer walls for the space between said walls, and heating means enclosed within said inner casing wall below the lowest compartment.

3. A device of the character described comprising an outer casing wall, an inner casing wall within and spaced from the outer wall and having openings to the space between said walls, a number of horizontal partitions within said inner wall provided with openings therethrough respectively and forming compartments each communicating through said first named openings with the space between said walls, a pair of spaced top walls connected with said outer and inner walls respectively, and having the space between them communicating with the space between said outer and inner walls, a rotary vertical shaft extending axially through said top walls and said partitions, an agitator device attached to said shaft above each of said partitions, a device for feeding material through said top walls above the upper partition into said inner casing wall, a water sealing device at the lower ends of said inner and outer walls for the space between said walls, a heating device enclosed within said inner wall below the lowest compartment and a partition closing said space between said inner and outer walls above the plane of the lowest one of said first named partitions.

4. A device of the character described com-

prising an outer casing wall, an inner casing wall spaced from the outer wall and having vapor passages into the space between said walls and material discharge openings into said space below said vapor passages, a partition closing said space below the plane of all of said passages and above said openings, a bottom wall in said inner casing below said material discharge openings, a number of horizontal partitions in said inner casing wall above said bottom wall forming compartments each communicating with the space between said inner and outer walls through certain of said passages, a vertical rotary shaft extending axially through said partitions, agitators attached to said shaft above the respective partitions, and a heater enclosed within said inner wall below said bottom wall.

5. A device of the character described comprising an outer casing wall, an inner casing wall spaced from the outer wall and having vapor passages into the space between said walls and material discharge openings into said space below said vapor passages, a partition closing said space below the plane of all of said passages and above said openings, a bottom wall in said inner casing below said material discharge openings, a number of horizontal partitions in said inner casing wall above said bottom wall forming compartments each communicating with the space between said inner and outer walls through certain of said passages, a vertical rotary shaft extending axially through said partitions, agitators attached to said shaft above the respective partitions, a heating device enclosed within said inner wall below said bottom wall and a water sealing device sealing the lower end of the space between said outer and inner casing walls and arranged to receive the material discharged from said material discharge openings.

EDWARD B. ROTH.
